UNITED STATES PATENT OFFICE.

EUGENE W. CALDWELL, OF NEW YORK, N. Y.

X-RAY APPARATUS.

Specification of Letters Patent.

Patented Feb. 27, 1917.

1,217,148.

Application filed July 15, 1911. Serial No. 638,628.

To all whom it may concern:

Be it known that I, EUGENE W. CALDWELL, a citizen of the United States, and resident of the city, county, and State of New York, have made certain new and useful Inventions Relating to X-Ray Apparatus, of which the following is a specification, taken in connection with the accompanying drawings, which form part of the same.

This invention relates especially to X-ray apparatus and may comprise polyphase high potential transformers which may have their primaries simultaneously connected to a polyphase supply circuit by an operating switch, there being a working circuit which may comprise an X-ray or other lighting tube, a series of Villard type valve tubes connecting each of said transformer secondaries to each side of said working circuit to deliver superimposed rectified current impulses thereto and operate said tube by substantially uniform direct current. The working circuit may if desired comprise a starting and equalizing coil tending to equalize the normal working current passing therethrough and provided with a magnetic core and a starting circuit which is preferably arranged to operate said starting coil and comprising a starting primary cooperating with its core to energize the same, a source of potential and a magnetic break operated by said core and contacts preferably connected to said operating switch to send intermittent high potential impulses through the working circuit until the normal working current is established therethrough, whereupon the working current may automatically hold open the magnetic break and allow the substantially uniform working current to actuate the tube at highest efficiency.

In the accompanying drawings showing in a somewhat diagrammatic way illustrative embodiments of this invention,

Figure 1 is a circuit diagram.

Fig. 2 is a circuit diagram showing another arrangement of Villard tube rectifiers in connection with polyphase transformers.

Fig. 3 is a detail showing in elevation a series of valve tubes.

Fig. 4 is a transverse section thereof.

Fig. 5 is an enlarged detail showing the construction of one of these tubes.

Fig. 6 shows a modified form of valve tube.

Fig. 7 shows still another form of valve tube.

In the illustrative forms of apparatus shown in the drawings, the polyphase transformers may be connected and operated in any desired way to produce in their secondaries polyphase alternating currents at potentials of 60,000 or more volts for X-ray tube work. Each of the transformer secondaries may be connected in any desired way with each side of the working circuit in which the X-ray tube or other high potential lighting tube or other device is located, by means of Villard or similar vacuum valve tubes, a number of such tubes being preferably used in series in each case so as to form a series of valve tubes delivering superimposed rectified current impulses from each of the transformer secondaries to the working circuit. In Fig. 1 a three-phase arrangement is shown, the transformer secondaries being connected in Y while the transformer primaries may of course be connected in any desired way with the supply circuit. The three-phase transformers may comprise the transformer secondaries 16, 17, 18 which may, if desired, be connected in each instance to the transformer primaries 20, 21 and 22 and if desired the transformer secondaries may be connected in Y by the connection 19. The direct current or working circuit may comprise the two sides 5 and 9 each of which may be connected with each of the transformer secondaries through a series of Villard type valve tubes which may comprise any desired number of tubes to secure the desired rectifying action at the operating voltage. In Fig. 1, only two tubes are diagrammatically shown in each series, the arrows indicating the direction of the current which these valve tubes allow to pass. The series of rectifying tubes 13 may connect the side 5 of the working circuit with the connection 10 of the transformer secondary 16 while the series of tubes 14 similarly connects this transformer secondary with the other side 9 of the working circuit. Similar series of valve tubes 11 and 12 connect the wire or connection 26 of the transformer secondary 17 with the two sides of the working circuit and the connector 6 of the transformer secondary 18 is similarly connected with the working circuit by the two series of valve tubes 7 and 8. When these transformers are operated the rectified high potential current impulses

delivered to the working circuit are superimposed and produce a substantially uniform direct current therein which may be used to operate an X-ray tube of any desired construction, such as 42, or any other lighting tube or other high potential device, if desired. The normal working current may, if desired, be further equalized by the use of a suitable equalizing or inductance coil therein which may be in the form of the coil 43 having a suitable magnetic core 144 coöperating therewith. This high inductance equalizing coil of course tends to prevent any variation in the current passing through the working circuit with which this coil is in series and with such an arrangement a substantially uninterrupted and uniform direct current can be secured as shown by oscilloscopes.

Such a uniform working current is highly desirable in X-ray work, since after the tube is started by any desired starting device the working current can be maintained constantly at the amount giving the highest tube efficiency with the minimum of undesirable radiation and other undesirable effects, such as destructive action on the tube itself. Practically speaking, the working current is limited by the amount of current which may be used without destructive or decidedly undesirable action on the tube and by keeping the current constantly at such safe maximum very much greater radiographic effects can be secured than by the use of the ordinary induction coils or mechanically rectified single phase transformers. Another arrangement of polyphase transformers and Villard type rectifying tubes is shown diagrammatically in Fig. 2, in which the two-phase transformer primaries 96 are shown as coöperating with the high potential secondaries 95. Both ends of each of these transformer secondaries may be connected with the bridge arrangement of rectifying tubes indicated so as to secure a substantially uniform working current in the working circuit 86, 90. The side 86 of this working circuit may be connected with the two series of valve tubes 91, 92, the ends of which connect with the terminals 87, 187 of the transformer secondary and also with the two coöperating series of valve tubes 93, 94 forming the bridge arrangement indicated and delivering the rectified current impulses along the working circuit connection 88 which leads to a similar bridge arrangement of tubes connected to the secondary of the other transformer. These superimposed direct current impulses in the working circuit are quite uniform and may be still further equalized by the use of suitable equalizing coils or devices as previously described.

The transformers shown in Fig. 1 may be conveniently operated by the arrangement of

circuits shown diagrammatically in connection therewith which may comprise a series of contacts 23 connected to different points in each of the transformer primaries so as to put more or less primary turns in circuit and correspondingly regulate the secondary potentials secured. These contacts may co-operate with the simultaneously operated contact arms 25 which may be conveniently mounted on a suitable switch bar 24 so as to be insulated from each other and simultaneously swung into engagement with the contacts 23 when the regulator switch handle 26 connected to the bar is operated. These switch arms may be connected by the wires 30, 29 and 31, 27 with the contacts 130, 129 and 127 of the three-pole double throw switch 32. The blades of this switch may as indicated be connected with the switch contacts 115, 126 and 106 which are connected through the wires 15, 26 and 6 with the other ends of the transformer primaries. By throwing this switch 32 upward so that its blades engage the contacts 130, 129 and 127 the transformer primaries are connected in delta, while when the switch 32 is swung downward so as to electrically connect all its switch blades by the through connection 33 the transformer primaries are connected in Y. The three-phase supply circuit 37, 40, 39 may be connected with the transformer primaries in any desired way as by the use of the operating switch 36 which when closed electrically connects the supply circuit with the wire 27, 31 and the switch arm 25 coöperating with the transformer primary 20. This operating switch also connects the supply circuit with the similar primary connections 28 and 29 so as to operate the transformers whenever this operating switch is closed. It is also desirable to have in connection with this operating switch a suitable starting switch or starting contacts so as to produce in the working circuit suitable high potential starting impulses when the operating switch is closed. This may be secured by providing the starting contacts 135, 138 in connection with the operating switch itself so that when this switch is closed the starting contacts are electrically connected and the starting circuit therethrough is closed so as to allow current from the starting battery 48 to pass through the wire 38 and the contact 45, of the magnetic break 143 which is normally closed by the light spring indicated and which may be provided with a suitable starting armature 142 coöperating with the magnetic core 144 of the starting and equalizing coil 43. This starting circuit may also comprise a suitable starting primary 44 coöperating with this magnetic core 144 and connected by the wire 35 with the starting contact 135. The current passing through this starting circuit when the operating switch 130

switch is first closed energizes the core 144 and this acts sufficiently on the starting armature 142 to cause the magnetic break to interrupt this starting circuit and send an 5 intermittent high potential impulse through the working circuit, the connections being of course preferably so arranged that this starting impulse acts in the same direction as the normal working current. If this 10 starting impulse or spark is insufficient to break down the starting resistance of the tube or other device and initiate the passage of the normal working current the light spring again closes the magnetic break and 15 a series of such starting impulses continues to be produced by the coil until the normal working current regularly passes through the working circuit and X-ray tube, for example, a suitable sparking condenser 47 being 20 if desired connected by the wires 46, 146 around the magnetic break as indicated to minimize sparking at that point. Thereupon the working current passing through the starting and equalizing coil 43 sufficiently 25 energizes its core to act on the starting armature and keep open the starting circuit so as to prevent any further irregular starting impulses and to allow the substantially uninterrupted uniform working current 30 to act alone in the tube or other translating device.

The Villard type tubes are especially desirable for use in rectifying such high potential currents as are desirable for X-ray work and the like which are of relatively small amperage, say, from a few milliamperes to two or three hundred milliamperes or so in ordinary work. These tubes, especially when used at relatively low 35 vacuum give good reliable results and are quite uniform in their action and are especially desirable because they are always ready to operate without requiring any special starting devices. It is, however, preferable 40 to use a series of such tubes in every instance to promote their uniformity of action and also to secure proper rectification of such high potential currents when the tubes are used at the relatively 45 low vacuum which seems desirable. A series of such tubes may be conveniently mounted to form a valve tube rectifying unit by the use of the valve tube rack shown in Figs. 3 and 4. The rack rods 50, 51 50 which may be made of suitable insulating material, such as varnished wood, vulcanite or the like, may be connected by the suitable metallic end connectors or brackets 49 so as to be rigidly held in position. A 55 number of suitable flexible tube clamps 52, which may be formed of sole leather or other suitable material may be strung upon these rack rods and be formed with suitable gripping holes to quite closely engage the 60 rods and with a central clamping aperture

to coöperate with the tube ends 60, as shown in Fig. 4. By forcing these tube clamps into the curved positions indicated in Fig. 3, their ends assume a sufficiently diagonal position with respect to the rack rods to securely 70 clamp them thereto and hold the valve tubes firmly in position, but without undesirable rigidity which might promote breakage. A suitable wire or the like 97 may connect the anode of the lower valve tube 53 with 75 the bracket or end connector 49 at the lower end of the rack and the intermediate wires or connectors 99 may similarly connect the intermediate valve tubes, anode to cathode so as to form a series arrangement, 80 the upper wire 98 connecting the cathode of the upper tube to the end connector or bracket 49 at the top of the tube rack, thus making an interchangeable valve tube rack or unit which may be readily replaced in 85 connecting the transformer secondaries with the working circuit.

It is highly desirable to have a self-regulating form of valve tube for this work and the form of tube shown in Fig. 5 is desirable 90 in this connection. The exhausted glass body 53 is formed with the projecting end 59 through which extends the terminal of the cathode which may as indicated be in the form of a spiral 55 of aluminum wire or 95 other material and the effective area of this negative electrode when the rectified current is passing through the tube may, if desired be increased by inserting therein a suitable cylindrical sheet metal electrode 56 which 100 may be forced into connection with the spiral wire, or if desired be suitably connected to the terminal in any other way and act alone as the cathode. The anode 58 is of relatively small area and its effective area is 105 still further reduced by being surrounded or loosely embraced by the small glass tube 160 which may be fused into the projecting end or anode chamber 60 of the glass body 110 of the tube and through which the anode terminal extends. This anode chamber 60 is provided with the usual restricted passage or neck 157 and this restricted passage is located within the exhausted tube body 53, so that there may be arranged thereon or in 115 connection therewith suitable salts 57, such as fused potassium or sodium hydrate capable of developing sufficient gas to reduce the vacuum when this restricted passage 157 becomes heated on the undesirable 120 increase of the tube vacuum. It is of course understood that these Villard type valve tubes are so proportioned that the effective anode surface is made so small in connection with the reduced chamber in which the 125 anode is located as to have the proper valve or rectifying action in connection with the large containing chamber and effective surface of the cathode. Another form of regulating valve tube which may be used in this 130

connection is indicated in Fig. 6 in which the anode 58 is located within the usual reduced chamber 60 connected through the restricted passage or neck 157 with the valve tube body 53. The enlarged cathode may be given the form of a concave cup 62 which may have a central hole 63 and be supported by the stem 54 mounted in a lateral extension 69 of the tube. Under normal conditions of desirable low vacuum the cathode stream is dispersed and the tube has the normal valve action. When, however, the tube vacuum becomes undesirably high the cathode stream is concentrated so as to strike the salt 57 mounted upon a suitable support 177 so as to evolve sufficient gas to reduce the vacuum and again disperse the cathode stream and stop the evolution of gas. The support 177 may be made adjustable within the tube by being mounted on a threaded stem 64 which may coöperate with a suitable nut 164 mounted in the tubular glass support 159 in the reduced end 59 of the tube. By securing a suitable operating weight 61 on the stem 64 the rotation of the threaded stem and consequent screw adjustment of the support 177 may be secured by holding the tube with its axis substantially horizontal and rotating it to the desired extent. Still another form of self-regulating valve tube is indicated in Fig. 7 in which the enlarged cathode 71 may be given the concave form indicated and be mounted on the metallic stem 73 in the extension 59 of the tube. The anode 58 is mounted in the usual way in the other end of the tube beyond the restricted passage or neck 157 of the anode chamber 60 and may have electrically connected therewith by the wire 72 or otherwise a suitable electrode 66 arranged in a suitable depression 70 in the tube and surrounded with a mass of high insulation 65. When the vacuum in the tube becomes undesirably high the potential difference between the cathode and the anode is correspondingly increased and this increases the electrical attraction between the cathode stream 68 and the electrode 66 so as to attract the cathode stream toward the electrode and cause its impingement upon the gas producing salt 57 on a suitable support 67 mounted in the tube. When, however, the vacuum is sufficiently reduced to restore normal conditions, the cathode stream no longer impinges sufficiently on the support to cause further action on the salt carried thereby.

While of course any suitable form of X-ray tube may be used in connection with this apparatus, a desirable tube is indicated in Fig. 1 in which the cathode 75 may be formed of thin aluminum or other material substantially transparent to X-rays while impervious to the undesirable radiation. This cathode may be supported in

any desired way on a stem within the extension indicated as connected to the corrugated body 42 of the tube. This tube is adapted to work at high efficiency and to give good radiographic effects while developing a minimum amount of undesirable radiation. This tube 42 may be connected to the working circuit as indicated in Fig. 1 and it is desirable in order to secure best results to have a suitable milli-ammeter 75 such as 3 located in this working circuit. For many purposes it is also desirable to have a suitable luminous oscilloscope such as 1 in the working circuit and for radiographic work it is advantageous to have 80 such an oscilloscope mounted adjacent the ammeter so as to illuminate its dial when the tube is being operated. This may be effected by mounting the oscilloscope close to and preferably slightly above the dial 85 of the milli-ammeter which may be done by connecting it in series therewith and with the tube by the wires 4 and 41 so that the luminosity of the electrodes 2 will give some indication of the current passing and also 90 enable an accurate reading to be made of the adjacent milli-ammeter needle when desired.

Having described this invention in connection with a number of illustrative 95 embodiments, forms, proportions, arrangements and connections of parts, to the details of which disclosure the invention is not of course to be limited, what is claimed as new and what is desired to be secured 100 by Letters Patent is set forth in the appended claims.

1. In X-ray apparatus, three-phase transformers, an operating switch to simultaneously connect the primaries of said transformers to a three-phase supply circuit, a working circuit comprising an X-ray tube, a series of Villard type valve tubes connecting each of said transformer secondaries to each side of said working circuit to 110 deliver superimposed rectified impulses thereto, said working circuit comprising a starting and equalizing coil tending to equalize the normal working current passing therethrough, a magnetic core coöperating with said equalizing coil; a starting circuit comprising a starting primary co-operating with said core to energize the same, a source of potential, a magnetic break operated by said core in series with 120 said starting primary and contacts connected to said operating switch to send intermittent high potential impulses through said working circuit until the normal working current passes therethrough and holds 125 open said magnetic break.

2. In X-ray apparatus, three-phase transformers, an operating switch to simultaneously connect the primaries of said transformers to a three-phase supply circuit, a 130

- working circuit comprising a high potential vacuum tube, a series of vacuum valve tubes connecting each of said transformer secondaries to each side of said working circuit to deliver superimposed rectified impulses thereto, said working circuit comprising a starting and equalizing coil tending to equalize the normal working current passing therethrough, a magnetic core co-operating with said equalizing coil; a starting circuit comprising a starting primary co-operating with said core to energize the same, a source of potential, a magnetic break operated by said core in series with 5 said starting primary and contacts connected to said operating switch to send intermittent high potential impulses through said working circuit until the normal working current passes therethrough and holds open said magnetic break; an ammeter in said working circuit and a luminous oscilloscope in said working circuit and co-operating with said ammeter to illuminate the same. 70
6. In X-ray apparatus, polyphase transformers, a high potential working circuit comprising a high potential vacuum tube, one or more self-regulating valve tubes connecting each of said transformer secondaries to each side of said working circuit to 75 deliver superimposed rectified impulses thereto, said working circuit comprising a starting and equalizing coil tending to equalize the normal working current passing therethrough, a magnetic core co-operating with said equalizing coil, a starting circuit comprising a starting primary co-operating with said core and adapted to be connected to a source of potential to energize said core and a magnetic break operated by said 80 core in series with said starting primary to send intermittent high potential impulses through said working circuit until the normal working current passes therethrough. 85
7. In X-ray apparatus, polyphase transformers, an operating switch to simultaneously connect the primaries of said transformers to a polyphase supply circuit, a working circuit comprising an X-ray tube, a series of Villard type valve tubes connecting each of said transformer secondaries to each side of said working circuit to 90 deliver superimposed rectified impulses thereto, said working circuit comprising a starting and equalizing coil tending to equalize the normal working current passing therethrough, a starting circuit comprising a starting primary co-operating with said coil to energize the same, a source of potential, a magnetic break operated by 95 said coil in series with said starting primary and contacts connected to said operating switch to send intermittent high potential impulses through said working circuit until the normal working current passes 100 therethrough. 105
8. In X-ray apparatus, polyphase transformers, an operating switch to simultaneously connect the primaries of said transformers to a polyphase supply circuit, a working circuit comprising an X-ray tube, a rectifying device connecting each of said transformer secondaries to each side of said working circuit to deliver superimposed rectified impulses thereto, said working circuit comprising a starting and equalizing coil tending to equalize the normal working current passing therethrough; a starting circuit comprising a starting primary co-operating with said coil to energize the 110 115
5. In X-ray apparatus, polyphase transformers, an operating switch to simultaneously connect the primaries of said transformers to a polyphase supply circuit, a working circuit comprising an X-ray tube, a series of Villard type valve tubes connecting each of said transformer secondaries to each side of said working circuit to deliver superimposed rectified impulses thereto, said working circuit comprising a starting and equalizing coil tending to equalize the normal working current passing therethrough, a magnetic core co-operating with said equalizing coil; a starting circuit comprising a starting primary co-operating with said core to energize the same, a source of potential, a magnetic break operated by said 120 125 core in series with said starting primary 130

- same, a source of potential, a magnetic break operated by said coil in series with said starting primary and contacts connected to said operating switch to send intermittent high potential impulses through said working circuit until the normal working current passes therethrough.
9. In X-ray apparatus, polyphase transformers, a working circuit comprising a high potential tube, a rectifying device connecting each of said transformer secondaries to said working circuit to deliver superimposed rectified impulses thereto, said working circuit comprising a starting and equalizing coil tending to equalize the normal working current passing therethrough, a magnetic core coöperating with said equalizing coil, a starting circuit comprising a starting primary coöperating with said core and adapted to be connected to a source of potential to energize said core and a magnetic break operated by said core and in series with said starting primary to send intermittent high potential impulses through said working circuit until the normal working current passes therethrough.
10. In X-ray apparatus, polyphase transformers, a working circuit comprising an X-ray tube, a rectifying device connecting each of said transformer secondaries to said working circuit to deliver superimposed rectified impulses thereto, said working circuit comprising a starting and equalizing device tending to equalize the normal working current passing therethrough and a starting circuit coöperating with said starting device to send an increased potential impulse therethrough and promote the passage of the normal working current.
11. In X-ray apparatus, polyphase transformers, a working circuit comprising an X-ray tube; a rectifying device connecting each of said transformer secondaries to said working circuit to deliver superimposed rectified impulses thereto, said working circuit comprising a starting and equalizing device tending to equalize the normal working current passing therethrough and an operating switch operating said transformers and sending a starting current through said starting device to send a high potential impulse through said working circuit promoting the passage of the working current therethrough.
12. In X-ray apparatus, polyphase transformers, a working circuit comprising an X-ray tube, a rectifying device connecting each of said transformer secondaries to said working circuit to deliver superimposed rectifying impulses thereto of a potential suitable for X-ray tube work, said working circuit comprising an equalizing device tending to equalize the normal working current passing therethrough.
13. In X-ray apparatus, polyphase high potential supply circuits, a working circuit

comprising an X-ray tube, a high potential vacuum tube rectifying device connecting each of said supply circuits to said working circuit to deliver superimposed rectified impulses thereto of a potential suitable for X-ray tube work, said working circuit comprising an equalizing device tending to equalize the normal working current passing therethrough.

14. In X-ray apparatus, polyphase transformers, a working circuit comprising an X-ray tube, one or more Villard type valve tubes connecting each of said transformer secondaries to each side of said working circuit to deliver superimposed rectified impulses thereto, said working circuit comprising an equalizing coil tending to equalize the normal working current passing therethrough.

15. In X-ray apparatus, polyphase transformers, a working circuit comprising an X-ray tube and one or more Villard type valve tubes connecting each of said transformer secondaries to each side of said working circuit to deliver superimposed rectified impulses thereto.

16. In high potential vacuum apparatus, polyphase transformers, a working circuit comprising a high potential vacuum tube, one or more Villard type valve tubes connecting each of said transformer secondaries to each side of said working circuit to deliver superimposed rectified impulses thereto, said working circuit comprising an equalizing coil tending to equalize the normal working current passing therethrough.

17. In high potential vacuum apparatus, polyphase transformers, an operating switch to simultaneously connect the primaries of said transformers to a polyphase supply circuit, a working circuit comprising a high potential vacuum tube, a series of Villard type valve tubes connecting each of said transformer secondaries to each side of said working circuit to deliver superimposed rectified impulses thereto, said working circuit comprising a starting and equalizing coil tending to equalize the normal working current passing therethrough; a starting circuit comprising a starting primary coöperating with said coil to energize the same, a source of potential, a magnetic break operated by said coil in series with said starting primary and contacts connected to said operating switch to send intermittent high potential impulses through said working circuit until the normal working current passes therethrough.

18. In high potential vacuum apparatus, polyphase transformers, an operating switch to simultaneously connect the primaries of said transformers to a polyphase supply circuit, a working circuit comprising a high potential vacuum tube, a rectifying device connecting each of said transformer second-

- aries to each side of said working circuit to deliver superimposed rectified impulses thereto, said working circuit comprising a starting and equalizing coil tending to equalize the normal working current passing therethrough; a starting circuit comprising a starting primary co-operating with said coil to energize the same, a source of potential, a magnetic break operated by said coil 5 in series with said starting primary and contacts connected to said operating switch to send intermittent high potential impulses through said working circuit until the normal working current passes therethrough.
- 10 19. In high potential vacuum apparatus, polyphase transformers, a working circuit comprising a high potential vacuum tube, a rectifying device connecting each of said transformer secondaries to said working circuit to deliver superimposed rectified impulses thereto, said working circuit comprising a starting and equalizing device tending to equalize the normal working current passing therethrough and a starting circuit co-operating with said starting device to send 15 an increased potential impulse therethrough and promote the passage of the normal working current.
